UNITED STATES PATENT OFFICE.

EINAR TAMMI, OF MILWAUKEE, WISCONSIN.

HINGE FOR SAFES.

1,326,305.

specification of Letters Patent. Patented Dec. 30, 1919.

Application filed May 20, 1918. Serial No. 235,624.

To all whom it may concern:

Be it known that I, EINAR TAMMI, a citizen of the United States, residing at Milwaukee, in the county of Milwaukee, in 5 the State of Wisconsin, have invented certain new and useful Improvements in Hinges for Safes, of which the following is a specification.

This invention relates to improvements 10 in safe construction. One object is to construct a safe having hidden hinges which cannot be detected from the outside while the safe door is in closed position so that strangers or burglars cannot remove the 15 door by tampering with the hinges. A further object is to provide a safe that is ornamental in appearance, impressive and pleasing to the eye.

With the foregoing and other objects in 20 view the invention consists in the combination and arrangement of parts to be hereinafter fully described, pointed out in the appended claims and illustrated in the accompanying drawing which forms a part of 25 this specification and in which—

Figure 1 is a fragmentary sectional view of my safe illustrating its construction.

Fig. 2 is a front view of Fig. 1.

Fig. 3 is a front view of the safe.

30 Fig. 4 is a side view of the form of hinge employed.

Fig. 5 is a top plan view of Fig. 4.

Like reference characters denote corresponding parts throughout the several views.

The reference numeral 1 denotes the body 35 of the safe provided with the door 2, the door jamb or that portion 2^a of the safe body contiguous to the periphery of the door being of hollow formation as is also the 40 door. To the inner surface of the outer wall of the door 2 I secure the hinge 3 by means of its shank 4 formed with the 45 perforations 5 to receive the rivets 6. The said shank 4 terminates in a curved leaf portion 7 disposed, while the door is in closed position, inside the hollow jamb 2^a, said curved leaf being formed with a heel 8 adapted to seat in a slight recess formed in the jamb 2^a, said leaf, further, being 50 integral with a neck portion 9 that terminates

in the rolled head 10 spaced away from the curved leaf by the recess 11 and formed with the perforation 12 to receive the pintle 13 that pivotally connects said head to the spaced ears 14, 14 disposed in the jamb 2^a. 55

I employ preferably two hinges of the type described, as shown in Fig. 3. Normally the hinges are completely hidden in the door and door jamb, that is, during the time the door is in closed position. As the 60 door is moved to open position the curved leaves 7 of the hinges move outwardly from the door jamb into the position shown in dotted lines in Fig. 1.

What is claimed is:—

1. A hinge for safes, adapted to be used on a door and door jamb of hollow construction, formed with a flat shank secured directly to the door and with a curved leaf portion adapted to move into and out of the door jamb, a heel formed upon said curved leaf portion and adapted to seat in a recessed portion of the door jamb, a rolled head integral with said curved leaf portion, and connection between said head and the 75 door jamb.

2. In a hinge for safes, adapted to be used on a door and door jamb of hollow construction, formed with a flat shank secured directly to the inner surface of the 80 outer wall of the door and with a curved leaf portion adapted to move into and out of the door jamb as the door is closed and opened, a heel formed upon said curved leaf portion and adapted to seat in a recessed 85 portion of the door jamb in the closed position of the door, a rolled head integral with said curved leaf but partially spaced away therefrom thus forming an arcuate slotted portion to afford clearance for the door 90 jamb, and connection between said head and the door jamb.

In testimony that I claim the foregoing as my own I have hereto affixed my signature in the presence of two subscribing witnesses. 95

EINAR TAMMI.
